SNUFF BOX ATTACHMENT

Walter F. Knox, Montrose, S. Dak.

Application October 11, 1935, Serial No. 44,600

6 Claims. (Cl. 206—37)

This invention relates to snuff box attachments, and the primary object thereof is to provide means associated with a snuff box for constantly retaining the snuff in a compacted mass, thereby to retain its inceptive moisture, until depletion.

A further object of the invention is to provide an attachment of this type which may be easily and quickly applied to snuff boxes, and re-applied to fresh boxes.

The invention still further aims to provide a device of this type which is of simple and economical construction and which embodies a minimum of parts.

15 In the drawing:

Fig. 1 is a top plan view of the invention with the cover removed;

Fig. 2 is a section on line 2—2 of Fig. 1, with the cover applied, and

20 Fig. 3 is a side elevation of the invention with the parts in fully extended position.

The invention is applicable to a circular box having a body 1, provided with a cover 2, and resides in a pair of members 3 and 4 of plate or leaf form which are pivotally connected at their inner ends by a pin 5, through the medium of knuckles 6 and 7 formed on the respective plates 3 and 4, the knuckles being rotatably mounted on the pin.

25 A coil spring 8 surrounds the pin and has elongated ends 9 and 10 which are secured, for example, by soldering 11 and 12, to the plates.

The plates extend radially of the body and in width substantially equal the depth of the box. 30 The plate 3 is formed with an extension 13 that is curved and conforms to the inner circumference of the body 1, the upper end of the extension being bent outwardly and downwardly to provide a lip 14 that fits over the top edge of the body 1 and clampingly engages the periphery thereof, thereby to fixedly hold the plate 3 with relation to the body of the box.

In use the cover 2 is first removed following which the members 3 and 4 are moved into engagement with one another and inserted in the body of snuff, with the lip 14 engaged over the periphery of the box as depicted in Figs. 1 and 2. The cover is then applied and the box turned over and tapped upon its bottom to effect initial expansion of the two lips 3 and 4. As the snuff is used or removed from the box, and as shown in Fig. 1, the leaf 3 being held fixed, the leaf 4 is moved about the pin 5 due to the action of the spring 8 thereby compacting the mass of snuff against the leaf 3, which action constantly occurs as snuff is

removed from the box. In this way the mass of snuff in the box is held compact, thereby retaining its initial moisture. Fig. 1 illustrates the action supra, following the removal of a portion of snuff from the box.

It will thus be seen from the foregoing when the box is emptied the attachment may be removed and reapplied to a fresh box of snuff thereby enabling same to be continuously used.

In the use of the device in the instance of a circular box, as herein illustrated, it will be noted that the plates extend radially of the box and their pivotal connection occurs at the center of the box. Both of the plates have a length equal to the radius of the box, thereby assuring compacting 10 of the contents of the box until entirely exhausted.

What is claimed is:

1. In a snuff box, a circular body, a pair of plates each of a length substantially equaling the radius of the body, means for pivotally connecting the inner ends of the plates disposed at the center of the body, spring means for urging one of the plates in a direction to compress the mass of snuff between the plates, an extension on the outer end of the other of the plates engageable with the inner circumference of the body, the upper end of said extension having a lip which engages over the top edge of the body and with the periphery of the body to hold said other of the plates rigidly in position, and a cover for the box engageable over the lip.

2. In a snuff box, a circular body, a pair of plates each freely removable from the body of the box and of a length substantially equaling the radius of the body, means for pivotally connecting the inner ends of the plates disposed at the center of the body, spring means for urging one of the plates in a direction to compress a mass of snuff between the plates, means for removably but rigidly clamping the other of the plates to the body, and a cover for the box.

3. An attachment for circular snuff boxes composed of a pair of members each freely removable from the body of the box and of a length substantially equaling the radius of the body of the box, means for pivotally connecting the inner ends of the members, spring means for urging one of the members in a direction to compress a mass of snuff between said member and the other member, and means for removably clamping said first member in fixed relation to a snuff box.

4. An attachment for circular snuff boxes in accordance with claim 3, wherein the clamping means is composed of a lip which is formed to

engage over the top edge and periphery of the box.

5. In a circular snuff box attachment, a pair of pivotally connected spring pressed members receivable in the box and extending radially thereof and each freely removable therefrom, and means to clamp one of the members to the box so that the other member will hold the mass of snuff under tension against the first named member.

6. An attachment for snuff boxes including a pair of movably connected members, means engaging one of the members for exerting constant tension thereon to move the snuff against the other, and freely removable means engaging a side wall of the box to fixedly secure said other member to the box and whereby both members are freely removable from the box as a unit.
